LEROY C. DOANE, OF MERIDEN, CONNECTICUT, ASSIGNOR TO THE MILLER COMPANY, OF MERIDEN, CONNECTICUT, A CORPORATION OF CONNECTICUT

LIGHTING FIXTURE

Application filed August 8, 1929. Serial No. 384,352.

The present invention relates to lighting fixtures and is particularly directed toward ceiling lighting fixtures having shielded light sources.

5 The present invention contemplates a ceiling lighting fixture adapted to employ a plurality of incandescent lamps as light sources and provided with a translucent glass plate underneath the light sources to diffuse the 10 light downwardly and with a narrow opaque band about the center of the light sources to screen off direct light, thereby reducing glare.

15 The invention also contemplates a fixture of this type wherein the filament shield and diffusing plate are detachably secured to parts of the fixture which are permanently carried by the ceiling outlet box.

20 The accompanying drawings show, for purposes of illustrating the present invention, one of the many possible embodiments in which it may take form, it being understood that the drawings are illustrative of the invention rather than limiting the same.

In these drawings:

25 Figure 1 is a top plan view of the lighting fixture;

Figure 2 is a vertical sectional view with parts in elevation; and

30 Figure 3 is a perspective view of the fixture from underneath.

35 In the form of construction shown in the drawings, the fixture is illustrated as more particularly designed for use as a bedroom fixture and adapted to be secured to the ceiling. As here shown the supporting device for the fixture includes a hickey 10 adapted to be threaded on the stud outlet box or other support. This hickey carries a short nipple 11 to which is secured a coupling 12. The 40 coupling carries a depending stem 13.

The fixture is provided with three lamp sockets indicated at 14. These lamp sockets are carried on a disk 15 secured as here shown in one of the steps 16 of a stepped canopy 17. 45 The disk 15 overlies the upper face of the coupling 12 and is thereby adapted to support the canopy and sockets in place. It is apertured as indicated at 19 to accommodate the necks of the lamp bulbs L which are carried in the sockets 14. These sockets are

spaced so as to carry the lamp bulbs L on the vertical axis with the bulbs spaced as close as possible to the center stem.

50 The lower part of the stem 13 is surrounded by a tube 20. This tube is slidably carried by the stem and is provided with a clamping screw 21 adapted to enter into one or the other of the holes indicated at 22, these holes being spaced according to the lengths of lamp bulbs to be used in the fixture. The tube 20 also carries a filament shield. This filament shield is in the form of a sheet metal stamping having substantially vertical walls 24 and apertures 25 to accommodate the lamp bulb. The stamping 23 is permanently secured to the tubing 20 and when the screw 21 is in the proper hole in the stem 13, the filament shield will be held at approximately the center of the lamp bulb. The stem 20 also carries a hickey 26 which supports a diffuser 27 preferably in the form of a large flat glass disk. The diffuser is held in place by a nut 28 threaded up against an ornamental cast disk 29.

55 When the fixture is installed, it may appear substantially as indicated in Figure 3. The band 24 of the filament shield will cut off the horizontally emitted beams of light and hence will reduce glare. The glass disk 27 and the filament shield 24 are preferably proportioned so that no direct rays can pass between 60 the lower part of the filament shield and the upper edge of the glass disk. This condition is indicated by the dot and dash line 30 in the left of Figure 2. The diffuser will receive all of the downwardly directed light from 65 the lamp bulbs and will diffuse it to provide a soft even illumination. There will be ample upwardly directed light for ceiling illumination but no horizontally emitted direct light to produce glare.

70 It is obvious that the invention may be embodied in many forms and constructions within the scope of the claims, and I wish it to be understood that the particular form shown is but one of the many forms. Various 75 modifications and changes being possible, I do not otherwise limit myself in any way with respect thereto.

What is claimed is:

1. A lighting unit comprising a central 100

stem, a plurality of downwardly opening lamp sockets spaced about the stem, incandescent lamps in the sockets with their bulbs adjacent the stem, a large diameter diffuser carried by the stem below the lamp bulbs, and an opaque filament shield in the form of a narrow metal band supported from the stem and about the middle portion of the bulbs.

2. A lighting unit comprising a central stem, a plurality of downwardly opening lamp sockets spaced about the stem, incandescent lamps in the sockets with their bulbs adjacent the stem, a large diameter diffuser carried by the stem below the lamp bulbs, and an opaque filament shield in the form of a narrow metal band supported from the stem and about the middle portion of the bulbs, the shield being adjustable to various heights according to the length of different lamp bulbs.

3. A lighting unit comprising a central stem, a plurality of downwardly opening lamp sockets spaced about the stem, incandescent lamps in the sockets with their bulbs adjacent the stem, a tube slidably carried on the stem, a large diameter diffuser carried by the tube below the lamp bulbs, and an opaque filament shield in the form of a narrow metal band supported from the tube and about the middle portion of the bulbs.

4. A lighting fixture comprising a canopy, a plurality of downwardly opening lamp sockets housed therein, incandescent lamps in the sockets, a stem extending downwardly from the canopy, a filament shield carried by the stem and having holes to receive the lamp bulbs and a substantially vertical band to cut off horizontal rays from the lamp filament, and a diffuser carried by the stem below the lamps and extending beyond the lamps.

5. A lighting fixture comprising a canopy, a plurality of downwardly opening lamp sockets housed therein, incandescent lamps in the sockets, the canopy having an apertured bottom wall to accommodate the necks of the lamps and conceal the sockets, a stem extending downwardly from the canopy, a filament shield carried by the stem and having holes to receive the lamp bulbs and a substantially vertical band to cut off horizontal rays from the lamp filament, and a diffuser carried by the stem below the lamps and extending beyond the lamps.

55. 6. A ceiling lighting fixture comprising a canopy, a horizontal disk secured to the inside of the canopy, a plurality of lamp sockets carried by the disk, the canopy having openings below the sockets to accommodate the necks of incandescent lamps carried by the sockets, a central supporting stem passed through the canopy and disk and having an abutment to engage the disk and support the fixture, and a detachable filament shield and diffusing glass disk supported from the stem

with the shield about the lamp filament and the glass disk below the lamps.

Signed at Meriden, in the county of New Haven, and State of Connecticut, this 5th day of August, 1929.
